TOBACCO PIPE

George W. Rehfeld, Manhattan, Kans.

Application April 17, 1952, Serial No. 19,359

Term of patent 14 years

(Cl. D85—8)

To all whom it may concern:

Be it known that I, George W. Rehfeld, a citizen of the United States, residing at Manhattan, in the county of Riley and State of Kansas, have invented a new, original, and ornamental Design for a Tobacco Pipe, of which the following is a specification, reference being had to the accompanying drawing, forming part thereof.

Fig. 1 is a perspective view of a tobacco pipe showing my new design;

Fig. 2 is a side view thereof;

Fig. 3 is a plan view thereof;

Fig. 4 is an end view thereof; and

Fig. 5 is an opposite end view thereof.

I claim:

The ornamental design for a tobacco pipe, as shown.

GEORGE W. REHFELD.
